UNITED STATES PATENT OFFICE.

GUSTAV BERNHARD PETSCHÉ, OF PHILADELPHIA, PENNSYLVANIA, ASSIGNOR TO THE SOUTHWARK FOUNDRY & MACHINE COMPANY, OF PHILADELPHIA, PENNSYLVANIA, A CORPORATION OF PENNSYLVANIA.

REVERSING MECHANISM FOR STEAM-ENGINES.

972,402.

Specification of Letters Patent. Patented Oct. 11, 1910.

Application filed October 20, 1905. Serial No. 283,580.

To all whom it may concern:

Be it known that I, GUSTAV B. PETSCHÉ, a subject of the Emperor of Germany, residing in the city and county of Philadelphia, in the State of Pennsylvania, have invented a certain new and useful Improvement in Reversing Mechanism for Steam-Engines, of which the following is a true and exact description, reference being had 5 to the accompanying drawings, which form a part thereof.

My invention relates to steam engines, particularly to that class known as reversing engines and used in rolling mills, and it has 15 for its object to provide mechanism whereby the throttle valve controlling the admission of steam to the engine will be automatically closed during the adjustment of the engine valves to reverse the engine and opened as 20 the reversing operation is completed.

By preference I effect the shifting of the valves to reverse the engine through a reversing cylinder and piston, the cylinder having a valve which controls its admission 25 and exhaust which valve is directly actuated by the reversing lever aforesaid.

My invention consists in certain features of construction and arrangement, which are 30 pointed out in detail in the claims annexed to and forming a part of this specification.

The nature of the invention and its general purpose will be best understood as a whole as described in connection with the drawings in which it is illustrated in connection with a compound reversing engine, the valve actuating mechanism of which is 35 also new with me and forms the subject matter of my co-pending application for Letters Patent filed October 20th, 1905 Serial 40 Number 283,579.

In these drawings: Figure 1, is a plan view of the engine with my improvements applied thereto. Fig. 2, a side elevation of the engine. Fig. 3, a longitudinal vertical section through the reversing cylinder and its connections and attachments. Fig. 4 is a front elevation of the throttle valve and its actuating mechanism, and Fig. 5, a section through the valve and its mechanism on the 45 line 5-5 of Fig. 4.

A, is the low pressure and B, the high pressure cylinder of the engine, the piston

rod of the low pressure cylinder being indicated at A', and shown as coupled through a cross-head C, and connecting rod C', with 55 the crank C², of the engine shaft D.

E, E, are parallel eccentrics secured on the shaft D, on either side of an angularly set eccentric F. Of these eccentrics, those marked E, E, are coupled by rods E', with 60 the lug G', at the upper end of the valve link G, while the eccentric F, is coupled by the rod F', with the lugs G², at the lower end of the link. The link is provided with centrally located trunnions G⁵, by which it 65 is supported on a rock lever H, supported in turn on a shaft K.

I, and J, are link blocks slidingly supported in the link G, the block I, being connected with the valve of the low pressure 70 cylinder through the rod I', rock lever I², and rod I³, while the block J, is connected with the valve of the high pressure cylinder through the rod J', rock lever J², rod J³, rock lever J⁴, and rod J⁵. The link blocks 75 are adjusted in the link through connecting rods M', L', connected respectively to levers L, M, pivoted on the shaft K, and provided with counterweights L², M², and also with angularly set lever arms L³, M³, which in 80 turn are connected through rods L⁴, M⁴, and sliding clamping heads L⁵, M⁵, with the slotted levers N, N', which are firmly secured to a rock shaft O, having a lever arm O', which in turn is connected through rods 85 O², with the crosshead P³, which, as shown in Fig. 3, is connected with the piston rod P², attached to a piston P', moving in the reversing cylinder P, an extension P⁴, of the rod having attached to it a plunger P⁵, 90 which moves between adjustable stop heads R, R', preferably formed as shown and cylindrical cavities adapted to receive the plunger and provided with restricted air escapes, as indicated at R⁸, R⁸. The stop 95 heads R, R', are held in position and adjusted by means of the right and left threaded rods R⁴, by their heads R³, R³, and having attached to them worm wheels R⁵, R⁵, which are engaged by appropriate 100 worms on a shaft R⁶, which extends up into the operator's bridge and is provided with the usual hand wheel, as shown in Fig. 2.

Steam admission and exhaust to the revers-

ing cylinder P, is effected by the motion of the valve Q, actuated through the connection indicated at Q'.

To the extent above described, the engine 5 illustrated is that described and, to the extent of its novelty, claimed in my before mentioned co-pending application. The movement of the piston in the reversing cylinder effecting the oscillatory movement 10 on the slotted levers N, N', and through them and the connections described, shifting the link blocks from one side of the center of the link to the other with a consequent shifting of the connected valves to reverse 15 the engine, the cut off of both connected valves being simultaneously regulated by the adjustment of the stop blocks R, R', which regulate the amount of movement of the piston P', in the reversing cylinder and consequently 20 the extent of the oscillatory movement of the levers N, N', and of the parts connected therewith, the device also providing for the independent regulation of the cut-off of either cylinder by the adjustment 25 of the sliding heads L⁵, M⁵, in the slotted levers N, N'.

Passing now to a description of the parts directly connected with my present invention, it will be seen that the valve actuating 30 rod Q', of the reversing cylinder P, is connected through a lever arm Q², with the reversing lever Q⁴, pivoted at Q³, and having an arm Q⁵, which through rod Q⁶, the pivoted levers indicated at Q⁷, and rod Q⁸, is 35 connected to actuate the throttle valve of the engine indicated at T, said throttle valve being in the steam supply pipe S, S', indicating the receiver connecting the high and low pressure cylinders.

40 The connection of the reversing lever with the throttle valve is such that the valve will be closed in the intermediate position of the lever and opened as the lever is shifted in either direction from such intermediate position. My preferred construction is that shown in the drawings in which the rod Q⁸, 45 is connected to a lever arm T¹², secured to a rock shaft T⁹, to which is also secured a link T⁸, of a toggle joint valve actuating device, said link being pivotally connected with the other link T¹², of the device which, as shown, 50 is coupled to the valve stem. The construction and connection being such that the valve is closed when the links of the toggle joint are in parallel position or alinement and opened as the toggle joint links move in either direction from such parallel position. By preference I provide a locking detent 55 which will engage and hold the links in alinement and consequently hold the valve closed, this device, as illustrated, consisting of a segment T¹⁰, secured to the rock shaft T⁹, and having a notch T¹¹, and a detent which, 60 as shown, consists of a lever T¹⁵, pivoted on arms T¹⁴, secured to the standards T¹³, which

support the shaft T⁹, the lever being properly weighted and having a roller T¹⁶, which rides on the segment T¹⁰, and engages the notch T¹¹, when the toggle joint members are in alinement. 70

The toggle joint valve actuating device is shown as connected with a sliding head T⁵, moving in a guideway T⁶, and connected to a valve spindle T⁴, supporting the cylindrical valve T³, moving in a cylinder T', 75 which connects the supply main S², with the steam pipe S, and when moved downward comes in contact with the seat indicated at T².

It will be seen that when the reversing 80 lever Q⁴, is shifted to intermediate position the toggle valve actuating device will have its members brought into alinement and the valve will be closed and held closed by the engagement of the detent with a notched 85 segment, also that the shifting of the reversing lever in either direction will cause the toggle members of the valve actuating mechanism to assume an angular position to each other and will open the throttle 90 valve, while at the same time steam will be admitted to one side or the other of the reversing cylinder and the reversal of the valves accomplished through the mechanism described. 95

The throttle valve construction shown in Figs. 4 and 5 involves the invention which forms the subject matter of my co-pending application filed October 20th, 1905, Serial Number 283,581. 100

Having now described my invention, what I claim as new and desire to secure by Letters Patent is—

1. In a reversing engine, a lever connected to shift the valve actuating mechanism and reverse the engine, in combination with a throttle valve for regulating the admission of steam to the engine, means connecting the reversing lever aforesaid with said throttle valve whereby said valve is closed in the intermediate position of the lever and gradually opened as the lever moves in either direction from said intermediate position, and an automatic detent acting to engage the valve actuating connection and hold the valve in closed position. 110

2. In a reversing engine, a throttle valve in combination with a toggle joint mechanism for opening and closing said valve, said mechanism being arranged to close the 120 valve when its jointed links are in alinement and to open it when the said jointed links are moved out of alinement in either direction, means for shifting the engine valves to reverse the motion of the engine, a reversing 125 lever for actuating said means, and connections from said lever to the toggle joint actuating device of the throttle valve whereby its jointed links are moved to parallel position and the valve closed when the lever is 130

in intermediate position and whereby the shifting of the lever in either direction acts to move the jointed links from said parallel position and open the valve.

5 3. In a reversing engine, a throttle valve in combination with a toggle joint mechanism for opening and closing said valve, said mechanism being arranged to close the valve when its jointed links are in alinement 10 and to open it when the said jointed links are moved out of alinement in either direction, a notched segment moving with one of the jointed links, a detent supported on said segment and arranged to engage the notch 15 therein when the valve is closed, means for

shifting the engine valves to reverse the motion of the engine, a reversing lever for actuating said means, and connections from said lever to the toggle joint actuating device of the throttle valve whereby its jointed 20 links are moved to parallel position and the valve closed when the lever is in intermediate position and whereby the shifting of the lever in either direction acts to move the jointed links from said parallel position and 25 open the valve.

GUSTAV BERNHARD PETSCHE.
